UNITED STATES PATENT OFFICE.

MORRIS VICTORSOHN, OF BROOKLYN, NEW YORK.

MOTOR RESETTER.

Application filed September 19, 1922, Serial No. 589,048. Renewed January 5, 1924.

To all whom it may concern:

Be it known that I, MORRIS VICTORSOHN, a citizen of the United States, residing at Brooklyn, in the county of Kings and State 5 of New York, have invented certain new and useful Improvements in Motor Resetters, of which the following is a full, clear, and exact specification.

This invention relates to motor resetters 10 for rewinding or resetting mechanical motors of the type disclosed in my pending application filed April 17, 1922, Ser. No. 554,278.

The object of this invention is to provide 15 for varying the throw of the weighted arm of the motor by the resetting device, whereby said motor and resetter may be adapted for use in casings of different sizes. Other objects will appear as the description 20 proceeds.

The invention will be first hereinafter described in connection with the accompanying drawings, which constitute part of this specification, and then more specifically defined in the claims at the end of the 25 description.

In the accompanying drawings, wherein 30 similar reference characters are used to designate corresponding parts throughout the several views:—

Figure 1 is a broken side elevation of a motor and resetting device constructed in accordance with this invention.

Figure 2 is a detailed view, partly in section, of the adjustable members of the resetting device; and

Figure 3 is a broken plan view of the same parts.

In Figure 1 the mechanism of the motor 40 and resetter are shown mounted in a casing 1 having a slot 2 in its top and a shaft 3 journaled therein. Inasmuch as the details of the motor and resetter are fully disclosed in my pending application hereinbefore mentioned, they will be described here only in general.

The motor consists of a rotary member 50 actuated by a weight which falls by gravity and turns said rotary member, the motion of which may be transmitted to mechanism to be driven, such as the turntable of a phonograph, through a train of gears. The rotary member is here shown as mounted on the shaft 3 and as including a gear 4 and a ratchet disk having teeth 6, said disk being rotatable with said gear 4. One of the train

of gears for transmitting motion to mechanism to be driven is indicated at 5.

The weight 11 is mounted on an arm 8 adapted to rotate about the axis of the gear 60 4, said arm being pivoted at 9 to a plate 10 having such rotary movement. The inner end of said arm has a tooth 7 adapted to engage any one of the teeth 6 on the ratchet disk of the motor when said arm 65 is swung downward by the weight.

A segmental gear 14 is also adapted to rotate with the motor gear 4 and has a radially extending arm 13 on an extension 20 thereof, said arm 13 extending below 70 the weighted arm 8 and being connected thereto by a link 12, so that rotation of the segmental gear 14 from right to left or anti-clockwise will raise said weighted arm through the instrumentality of said arm 13 75 and link 12, the latter being pivotally attached at 17 and 18, respectively, to said arms 13 and 8. In order to regulate the throw of said weighted arm in resetting the motor, so that the swing of said arm may 80 be accommodated within casings of different sizes, the arm 13 and link 12 may either or both be made extensible as shown. Said arm 13, for instance, may comprise telescoping sections 19 and 31, the latter 85 having a socket to receive the former. Slots 22 may be formed in the walls of said socket in the member or section 31, and a bolt 27 may be passed through said section 19 and the slots 22 of the sections 31 for adjustably securing said sections together. The link 12 may be similarly formed of telescopic sections 25 and 26, the latter having a socket with slots 28 in its walls through

which a bolt 27 attached to the section 25 95 extend for adjustably securing said sections together. By this means it will be seen that the lengths of said arm 13 and link 12 may be changed to vary the throw of the weighted arm 8 in resetting the same. 100

To actuate the gear segment 14 for resetting the motor a hand lever 16 is provided, the same carrying a spring-pressed pawl 15 to engage said gear segment. The free end of said hand lever extends through 105 the slot 2 in the casing 1 and may be moved in said slot when the cover 30 therefor is displaced.

I claim:—

1. In a motor of the character described, 110 the combination with a swinging weighted arm, of a rotary member coaxial with said

arm, means for rotating said member, and an extensible link connecting said weighted arm to said rotary member for the purpose specified.

5. 2. In a motor of the character described, the combination with a weighted arm, of a rotary member coaxial with said arm, there being an arm on said rotary member extending below said weighted arm, an extensible link connecting said weighted arm with said lower arm for the purpose specified, and means for turning said rotary member.

3. In a motor of the character described, 15 the combination with a weighted arm, of a rotary member coaxial with said arm, there

being an extensible arm on said rotary member extending below said weighted arm, and a link connecting said weighted arm with said lower extensible arm for the purpose specified. 20

4. In a motor of the character described, the combination with a weighted arm, of a rotary member coaxial with said arm, there being an extensible arm on said rotary member 25 extending below said weighted arm, and an extensible link connecting said weighted arm with said lower extensible arm for the purpose specified.

In testimony whereof I have signed my 30 name to this specification.

MORRIS VICTORSOHN.
